H. M. RYDER

RAILWAY TRAFFIC CONTROLLING APPARATUS

Filed May 2, 1924

INVENTOR:

H. M. Ryder,
by A. R. Vehcill
his attorney

UNITED STATES PATENT OFFICE.

HARRY M. RYDER, OF FOREST HILLS BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 2, 1924. Serial No. 710,520.

To all whom it may concern:

Be it known that I, HARRY M. RYDER, a citizen of the United States, residing at Forest Hills Borough, in the county of Allegheny and State of Pennsylvania, have invented certain new and useful Improvements in Railway-Traffic-Controlling Apparatus, of which the following is a specification.

- 10 My invention relates to railway traffic controlling apparatus, and particularly to apparatus of the type comprising vehicle carried governing means controlled by energy received from the trackway. More 15 particularly, my invention relates to the vehicle carried receiving apparatus through the medium of which energy is transferred from the trackway to the governing apparatus on the vehicle.
- 20 I will describe one form of receiving apparatus embodying my invention, and will then point out the novel features thereof in claims.

The accompanying drawing is a view, 25 partly diagrammatic, showing one form of receiving apparatus embodying my invention.

Referring to this drawing, the reference character *a* designates the front axle of a 30 railway vehicle, such as a locomotive, which vehicle normally moves in the direction indicated by the arrow over the track rails 1 and 1^a.

The track rails are supplied with alternating current from some suitable source such as an alternator *G* connected with the rails through a circuit controller 20. This circuit controller may be operated by any suitable means and when closed allows current to 40 flow through the rails from alternator *G*. It should be noted that this current flows down one rail, through axle *a*, and back through the other rail. The currents in the two rails 1 and 1^a therefore flow in opposite 45 directions at any given instant.

The reference character *B* designates the receiving apparatus in general. This apparatus comprises a plurality of magnetizable cores. Certain of these cores *A'*, *A²*, 50 *A³* and *A⁴* are arranged in advance of the front axle *a* above the track rail 1 and in inductive relation therewith. The remaining

cores *A⁵*, *A⁶*, *A⁷* and *A⁸* are arranged in advance of axle *a* above the track rail 1^a and in inductive relation therewith. 55

Each of the cores *A* is provided with a winding of some conductive material such as copper wire and here designated by the reference character *D* with a suitable distinguishing exponent. 60

A condenser 12 is connected across the terminals of windings *D'* and *D²* for the purpose of tuning these windings to approximate resonance at the frequency of alternator *G*. For a similar purpose a condenser 13 is connected across windings *D³* and *D⁴*, a condenser 14 is connected across windings *D⁵* and *D⁶*, and a condenser 15 is connected across windings *D⁷* and *D⁸*. 65

It will thus be clear that the receiving apparatus may be considered as consisting of a plurality of receiving elements each including two windings *D* tuned by a condenser. 70

It will be obvious from the drawing that 75 the various parts may be so connected that the voltages produced in all the receiving elements by alternating currents flowing in opposite directions in the two track rails at any instant are additive.

The terminals 10 and 11 of the receiving apparatus are connected with a relay *C*, and the voltage induced in the receiving apparatus is therefore available to energize relay *C* when alternating current is supplied to the track rails. The relay *C* may control suitable train-governing means in any desired manner. 85

One advantage possessed by receiving apparatus embodying my invention over the 90 usual type of receiving apparatus is a very marked improvement in efficiency since the construction here disclosed permits of a considerably greater number of turns for each winding *D* than is possible with the ordinary 95 construction.

Although I have herein shown and described only one form and arrangement of receiving apparatus embodying my invention, it is understood that various changes 100 and modifications may be made therein within the scope of the appended claims without departing from the spirit and scope of my invention.

Having thus described my invention, what I claim is:

1. Vehicle carried receiving apparatus comprising a plurality of receiving elements 5 in inductive relation with the track rails, each such element being tuned to approximate resonance at the same frequency, and all said elements being so connected that voltages induced in said elements by alternating currents flowing in opposite directions in the two track rails are additive.
2. Vehicle carried receiving apparatus comprising a plurality of receiving elements each comprising at least one winding in inductive relation with the track rails, a condenser connected in parallel with each said element, and all said elements being so connected that voltages induced in said elements by alternating currents flowing in 10 opposite directions at any instant in the two track rails are additive.
3. Vehicle carried receiving apparatus comprising eight magnetizable cores in which two pairs are located in inductive relation with each track rail, a winding on each core, all said windings being so connected in series that the voltages induced in 15 said windings by alternating current flow-

ing in opposite directions in the two track rails at any instant are additive, and four 30 condensers one connected in parallel with the windings on each pair of cores.

4. Vehicle carried receiving apparatus comprising a plurality of receiving elements located above each track rail and each element comprising at least one winding in inductive relation with the track rail and tuned to approximate resonance at a given frequency, all said elements being so connected that the voltages created in such 35 elements by alternating currents flowing in opposite directions in the two track rails at an instant are additive.

5. Vehicle carried receiving apparatus comprising a plurality of receiving elements 40 associated with each track and each comprising a winding in inductive relation with the corresponding track and a condenser in circuit with said winding, all said elements being so connected that the voltages created 45 in such elements by alternating currents flowing in opposite directions in the two track rails at an instant are additive.

In testimony whereof I affix my signature.

HARRY M. RYDER.

Certificate of Correction.

It is hereby certified that in Letters Patent No. 1,559,050, granted October 27, 1925, upon the application of Oscar Daniel Schwartz, of Hudson, New York, for an improvement in "Steering Mechanism for Vehicles," errors appear in the printed specification requiring correction as follows: Page 1, lines 48 and 49, strike out the words "of the rear truck"; same page, line 50, after the word "wheels" and before the period insert the words *of the rear truck at an angle different from the angle at which any of the other wheels of the vehicle are set at any given time*; same page, lines 78 to 81, strike out the words "at an angle different from the angle at which any of the other wheels of the vehicle are set at any given time"; page 4, lines 73 and 74, claim 7, strike out the words "about their separate axles" and insert the same to follow after the word "wheels" in line 75; and that the said Letters Patent should be read with these corrections therein that the same may conform to the record of the case in the Patent Office.

This Certificate supersedes Certificate of Correction issued December 15, 1925.

Signed and sealed this 19th day of January, A. D. 1926.

[SEAL.]

WM. A. KINNAN,
Acting Commissioner of Patents.
